UNITED STATES PATENT OFFICE.

JERVIS R. HARBECK, OF DETROIT, MICHIGAN, ASSIGNOR, BY MESNE ASSIGNMENTS, TO DETROIT CAN COMPANY, OF DETROIT, MICHIGAN, A CORPORATION OF NEW JERSEY.

PACKAGE-CAPPING MACHINE.

1,080,277.

Specification of Letters Patent.

Patented Dec. 2, 1913.

Application filed February 2, 1910. Serial No. 541,634.

To all whom it may concern:

Be it known that I, JERVIS R. HARBECK, a citizen of the United States of America, residing at Detroit, in the county of Wayne 5 and State of Michigan, have invented certain new and useful Improvements in Package-Capping Machines, of which the following is a specification, reference being had therein to the accompanying drawings.

10 The invention relates to machines for capping packages, and is more particularly designed for use in connection with paper packages.

15 The invention consists in the construction as hereinafter set forth.

In the drawings—Figure 1 is a vertical section through the machine; Fig. 2 is a plan view thereof; and Fig. 3 is a view similar to a portion of Fig. 1, showing the 20 parts in different positions.

25 The paper packages which are to be capped are usually constructed with cylindrical body portions, and the caps are provided with depending flanges, which closely fit said cylindrical bodies. On account of the flexible nature of the material, it is a somewhat difficult operation to engage the cap flange with the body, and I have therefore devised a machine for performing this 30 operation, constructed as follows:

A is an expansible annular guide preferably constructed of a series of guide fingers B pivotally mounted at C upon an annular frame or support D. Each of the 35 guide fingers B is provided with a thin plate E at its outer end adapted to be inserted within the flange of the cap, and forming a guide for directing the upper edge of the body of the package into engagement with said cap. The fingers B may 40 be adjusted in normal position by means of set screws F engaging bell crank arms G extending laterally from the pivots. There are also provided springs H, which yieldingly hold said bell crank arms against the 45 stop screws F.

The ring D is mounted upon a suitable frame, such as the bed or table I, having upward extensions J thereon. K is a 50 plunger having a shank L vertically adjustably secured in a bearing M upon the frame. This plunger is axially alined with the annular guide A, and is operated by suitable mechanism, such as the pinion N,

engaging a rack in the shank L and the 55 rack and pinion O and P for actuating the shaft Q on which the pinion N is mounted. R is a foot lever connected with the rack O and adapted when depressed to raise the shank L and plunger K. 60

With the construction as described, the plunger K in normal position is sufficiently below the annular frame D to permit of placing thereon the filled package, such as S. The cap for this package is placed with its 65 flange surrounding the guide fingers B and these are so positioned by proper adjustment of the stops F that the flange may be engaged therewith without difficulty. The operator then depresses the pedal R, which 70 raises the plunger K, forcing the package upward through the annular frame D and expansible guide A. During this upward movement, the upper edge of the package will come in contact with the guide fingers 75 B, which will yield, and are forced outward. In so doing, the thin plates E will force outward the flange of the cap, so as to permit the upper edge of the body to be directed therein. The continued upward 80 movement of the plunger will force the cap out of engagement with the guide fingers, and raise the package until nearly disengaged from the expansible guide. The operator may then lift the package out of engagement with the guide, and drop the 85 plunger ready for another operation.

What I claim as my invention is:

1. A package capping machine, comprising an annulus, a series of guide fingers 90 pivotally mounted thereon and each provided with a thin plate at its upper end, adjustable stops for positioning said fingers, and resilient means for yieldably holding said fingers against said stops, for the purpose described.

2. A package capping machine, comprising an annulus, a series of guide fingers pivotally mounted upon said annulus and having thin plates at their upper ends, outwardly-extending bell crank arms on said guide fingers, set screws forming adjustable stops for said bell crank arms, and springs for yieldingly holding said bell crank arms against said stops, for the purpose described. 100

3. A package capping machine comprising an expansible annular guide insertible with-

in the flange of the cap, and a plunger in axial alinement with said guide normally below the same a sufficient distance to permit of placing the body of the package thereon, and means for raising said plunger to force said package through the guide.

4. A package capping machine, comprising a vertically arranged expandable guide insertible within the flange of the cap, the latter being supported by the upper end of the guide, a support for holding the package in vertical position, and means for effecting a relative vertical movement between the support and the guide to force the body of the package through the guide into engagement with the cap.

5. A package capping machine, comprising an upright expandable annular guide insertible within the flange of the cap, the latter being supported solely by the upper end of said guide, a support for the package in axial alinement with the guide, and means for relatively moving said support and guide toward each other in a substantially rectilinear path to force said package through the guide and into engagement with the cap.

6. A package capping machine, comprising an upright expandable annular guide having a thin edge insertible within the flange of the cap and forming the sole support for the latter, a vertically arranged support for the package, and means for relatively moving said support and guide toward each other in a substantially rectilinear path to force the package through the guide and into engagement with the cap.

7. In a package capping machine, a combined guide and support for the cap, comprising an annular series of movable guide fingers insertible within the flange of the cap and adapted to support the latter during the capping operation, and yielding means acting upon the fingers to press the same inward.

8. In a package capping machine, a combined guide and support for the cap, comprising an annular series of movable guide fingers insertible within the flange of the cap and adapted to support the latter during the capping operation, stops for po-

sitioning said fingers, and resilient means for holding the fingers against the stops.

9. In a package capping machine, a combined guide and support for the cap, comprising an annular series of movable fingers insertible within the flange of the cap and adapted to support the latter during the capping operation, means for limiting the inward movement of the fingers, and yielding means for normally retaining the fingers at the limit of their inward movement.

10. A package capping machine, comprising an upright expandable annular guide insertible within the flange of the cap, the latter being supported by the upper end of said guide, and means for forcing the body of the package through said guide into engagement with the cap adapted upon a further movement to effect the lifting of the cap from the guide by the package.

11. A package capping machine comprising an upright expandable annular guide having a thin edge insertible within the flange in the cap and forming the sole support for the latter, a vertically arranged support for the package, and means for relatively moving said support and guide to force the package through the guide and into engagement with the cap, said means being adapted upon a further movement to effect the disengagement of the cap from the guide.

12. A package capping machine comprising an expandable annular guide insertible within the flange of the cap, a support for the package in axial alinement with the guide, and means for relatively moving said support and guide toward each other in a substantially rectilinear path to force said package through the guide and into engagement with the cap adapted upon a further movement to effect the disengagement of the cap from the guide by the package.

In testimony whereof I affix my signature in presence of two witnesses.

JERVIS R. HARBECK.
